UNITED STATES PATENT OFFICE.

ALESSANDRO VALENTE, MICHAEL CURZON, AND SAMUEL CURZON, OF LONDON,
ENGLAND.

SAFETY-RAZOR.

1,345,039.

Specification of Letters Patent. Patented June 29, 1920.

Application filed January 9, 1920. Serial No. 350,449.

To all whom it may concern:

Be it known that we, ALESSANDRO VALENTE, MICHAEL CURZON, and SAMUEL CURZON, subjects of the King of Great Britain, residing at London, England, have invented certain new and useful Improvements in and Connection with Safety-Razors, of which the following is a specification.

This invention relates to improvements in and in connection with safety razors.

The present invention has for its object to provide an improved construction of safety razor, which is economical in manufacture, *i. e.*, the chief components can be made of stampings; is of compact form; the components can be readily assembled and broken down, and while possessing the advantage of safety, is adapted for use in the same manner as that of an ordinary razor.

20 A further object in the fuller embodiment of the invention is to provide positioning means on the handle whereby the blade can be stropped.

A construction of safety razor under the invention comprises a handle which is extended in the same or substantially the same plane to form a single or double guard, thus forming a combined handle and guard in one piece. A single or double edged flat thin or otherwise wafer like blade is arranged to be clamped for rigidity by spring pressure between the guard and a clamping plate or backing, this clamping plate or backing having lugs stamped therefrom, which lugs pass through corresponding holes in the blade and in the combined handle and guard. The said lugs are so fashioned at the ends remote from the clamping plate or backing as to provide facilities for engaging and holding a pressure plate spring, the latter being so arched or bowed that when passed between and held by the aforesaid lugs a clamping or drawing together of the components is effected, to form an operative safety razor device.

In a fuller aspect of the invention, the handle has holes corresponding to those in the guard, so that by releasing the pressure spring to enable the components to be broken down at the guard end and assembling these parts at the handle end in the same relationship as when assembled on the guard end, stropping of the blade on an ordinary strop can be effected.

55 The accompanying drawings illustrate a

form of safety razor constructed under the present invention:—

Figures 1 and 2 are side views of the components assembled in operative position for shaving, Fig. 3 is an edge view thereof, 60 and Fig. 4 is a side view of the components assembled for stropping.

Referring to the drawings a handle *a* is extended in the same or substantially the same plane to form a double guard *b*, thus 65 forming a combined handle and guard in one piece. A double edged flat wafer like blade *c* is arranged to be clamped between the guard *b* and a clamping plate *d*. This clamping plate has lugs *e*, *e* stamped up 70 therefrom, which lugs pass through holes *f*, *f*, *g*, *g*, in the blade and guard respectively. The lugs *e*, *e* may serve as positioning means for the blade with respect to the guard. The said lugs at the ends remote 75 from the clamping plate engage and hold a pressure plate spring *h*, the latter being so arched or bowed that when passed between and held by the aforesaid lugs a clamping or drawing together of the components is effected to form an operative 80 safety razor device.

The handle *a* has holes *i*, *j* corresponding to the holes *g*, *g* in the guard so that by assembling the components at the handle 85 end in the same relationship as when assembled on the guard end, stropping of the blade on an ordinary strop can be effected.

What we claim is:—

1. A safety razor comprising a combined 90 handle and guard component, a clamping plate component, a blade interposed therebetween, a spring pressure element, upstanding portions on one component extending through the blade and the other component, 95 the said upstanding portions at the ends remote from their connection with the first mentioned component being so formed as to coöperate with the other component to engage and hold the said spring pressure element whereby a clamping or drawing together of the components is effected for the purpose described.

2. A safety razor comprising a combined 100 handle and guard component in one piece, 105 a clamping plate component, a blade interposed therebetween, a spring pressure element, upstanding portions on one component extending through the blade and the other component, the said upstanding por-

tions at the ends remote from their connection with the first mentioned component being so formed as to coöperate with the other component to engage and hold the said 5 spring pressure element whereby a clamping or drawing together of the components is effected for the purpose described.

3. A safety razor comprising a combined handle and guard component, a clamping plate component, a blade interposed therebetween, a spring pressure element serving also as positioning means for the blade with respect to the guard, upstanding portions on one component extending through the 10 blade and the other component, the said upstanding portions at the ends remote from their connection with the first mentioned component being so formed as to coöperate with the other component to engage and hold the said spring pressure element whereby a clamping or drawing together of the components is effected for the purpose described.

4. A safety razor comprising a combined handle and guard component, a clamping plate component, a blade interposed therebetween, a spring pressure element, upstanding portions on one component extending through the blade and the other component, the said upstanding portions at the ends remote from their connection with the first mentioned component being so formed as to coöperate with the other component to engage and hold the said spring pressure element whereby a clamping or drawing together of the components is effected, and means at the handle end whereby the components can be assembled for stropping in the same relationship as when assembled on the guard.

5. A safety razor comprising a combining handle and guard component, a clamping plate component, a blade interposed therebetween, a spring pressure element, lugs 45 on the clamping plate, said lugs passing through corresponding holes in the blade and the combined handle and guard, the lugs being so formed at the ends remote from the clamping plate, as to provide facilities for engaging and holding the spring pressure element whereby a clamping or drawing together of the components is effected for the purpose described.

6. A safety razor comprising a combined handle and guard component, a clamping plate component, a blade interposed therebetween, a pressure plate spring, lugs on the 55 clamping plate, said lugs passing through

corresponding holes in the blade and the combined handle and guard, the lugs being 60 so formed at the ends remote from the clamping plate as to provide facilities for engaging and holding the pressure plate spring whereby a clamping or drawing together of the components is effected for 65 the purpose described.

7. A safety razor comprising a combined handle and guard component in one piece, a clamping plate component, a blade interposed therebetween, a pressure plate spring, 70 lugs on the clamping plate said lugs passing through corresponding holes in the blade and the combined handle and guard, the lugs being so formed at the ends remote from the clamping plate as to provide facilities for engaging and holding the pressure plate spring whereby a clamping or drawing together of the components is effected for the purpose described.

8. A safety razor comprising a combined handle and guard component in one piece, a clamping plate component, a blade interposed therebetween, a pressure plate spring serving also as positioning means for the blade with respect to the guard, lugs on the 85 clamping plate, said lugs passing through corresponding holes in the blade and the combined handle and guard, the lugs being so formed at the ends remote from the clamping plate as to provide facilities for 90 engaging and holding the pressure plate spring whereby a clamping or drawing together of the components is effected for the purpose described.

9. A safety razor comprising a combined handle and guard component, in one piece, a clamping plate component, a blade interposed therebetween, a pressure plate spring, 95 lugs on the clamping plate, said lugs passing through corresponding holes in the blade 100 and the combined handle and guard, the lugs being so formed at the ends remote from the clamping plate as to provide facilities for engaging and holding the pressure plate spring whereby a clamping or 105 drawing together of the components is effected and means at the handle end whereby the components can be assembled for stropping in the same relationship as when assembled on the guard.

In testimony whereof, we affix our signatures.

ALESSANDRO VALENTE.
MICHAEL CURZON.
SAMUEL CURZON.
